UNITED STATES PATENT OFFICE.

PATRICK W. HYNES, OF CEDAR RAPIDS, IOWA.

CAR-REPLACER.

SPECIFICATION forming part of Letters Patent No. 409,103, dated August 13, 1889.

Application filed September 20, 1888. Serial No. 285,888. (No model.)

To all whom it may concern:

Be it known that I, PATRICK W. HYNES, a citizen of the United States, and a resident of Cedar Rapids, in the county of Linn and State 5 of Iowa, have invented certain new and useful Improvements in Car-Replacers; and I do declare the following to be a full, clear, and exact description of the invention, such as will enable others skilled in the art to which it applies 10 pertains to make and use the same, reference being had to the accompanying drawings, and to letters or figures of reference marked thereon, which form a part of this specification.

Figure 1 of the drawings is a representation 15 of this invention and is a cross-section of the replacer. Fig. 2 is a top view. Fig. 3 is a side view. Fig. 4 is a top view. Figs. 5 and 6 show bottom and side views of the pyramidal studs.

This invention has relation to devices for 20 replacing the wheels of a derailed car upon the track; and it consists in the construction and novel combination of parts, as hereinafter set forth.

The object of this invention is to provide a 25 simple and effective device to be used chiefly in connection with the ordinary car-frog in replacing a car upon the track.

In the accompanying drawings, the letter A designates the car-replacer, which is of oblong form. Its base is rectangular and its side walls parallel. Its ends B B are on equal 30 angles from the base-level and terminate at the laterally-inclined top of the car-replacer. (Indicated at C.) The ends B B are inclined 35 from the inclined top C downward, as also laterally and reversely to the top incline or in a direction away from the rail, as indicated in dotted lines at A A'. This top or upper surface has its longitudinal elements parallel 40 to the base; but it is inclined from side to side, its lower side being lower than the height of a rail. In constructing this replacer I prefer to make its body E of hard wood—such as solid oak—and to secure thereto the 45 plates F, of iron or steel, covering the base, top, and ends. The plates and body should be bound together by means of strong rivets having countersunk heads.

In the base of the car-replacer, near its ends, 50 are secured the small spikes or pyramidal studs g g, which are designed to provide a

purchase for the replacer when necessary. In the winter some thin soft pieces of wood are laid upon the surface when leveled, and upon these pieces the replacer is seated.

55

In operation the replacer is placed between the track for the inner wheels, while the ordinary car-frog is used to run the outer wheels over the rail. The car is then drawn so that the wheels are run on the replacer and frog. 60 As the car progresses, the flange of the outer wheel passes over the rail, while the inner wheel, being raised on the replacer, is guided by its slanting top to position on its rail without interfering with the operating of the frog 65 on the outside in such a manner as to break or overturn it—an accident which frequently happens when the ordinary camel back or wedge is used for the inner wheels. Time is therefore saved, and in winter, if a little care 70 and judgment are used, it performs its work generally on the first trial. The slant of the top of the replacer also enables the user to make the proper adjustment closer or farther from the rail, to secure the proper rise 75 for the wheel.

By using two of these car-replacers, the turning or slewing of a car-truck is facilitated. The replacers are arranged under a pair of wheels, so that the inclined top will face in 80 the direction toward which it is desired to turn the truck. Then, the car being moved, the wheels rolling on the incline of the replacer will slip off on the lower side, turning the truck as desired.

85

Having described this invention, what I claim, and desire to secure by Letters Patent, is—

The car-replacer having an inwardly-sloping upper surface and reversely or laterally 90 and outward sloping ends, said ends also sloping downward, and which car-replacer has its upper inward sloping and base portions provided with plates, the lower one of which is armed with points or spikes, substantially as 95 set forth.

In testimony whereof I affix my signature in presence of two witnesses.

PATRICK W. HYNES.
